UNITED STATES PATENT OFFICE.

FREDERIC P. MEYER, OF LANCASTER, WISCONSIN.

DRINKING-CUP.

1,089,425.

Specification of Letters Patent. Patented Mar. 10, 1914.

Application filed February 13, 1911. Serial No. 608,815.

To all whom it may concern:

Be it known that I, FREDERIC P. MEYER, a citizen of the United States, and a resident of Lancaster, in the county of Grant and State of Wisconsin, have invented certain new and useful Improvements in Drinking-Cups, of which the following is a specification.

This invention relates to drinking cups.

At the present time it is generally well recognized as a fact that use in common by different people of drinking cups and glasses is unsanitary and is a fruitful cause of spreading disease, both contagious and infectious. For this reason, the use of public drinking cups and glasses is generally looked upon with growing disfavor and in some communities is even prohibited by legal enactment. Where the use of public drinking glasses is prohibited, or when a person desires to avoid the use thereof, when available, it is rendered necessary that people, particularly when traveling, shall carry their own drinking cups, which is inconvenient, or shall purchase them when they wish to drink at a public drinking place, which is some times impossible, and also involves more or less expense.

The object of the present invention is to provide a drinking cup which will be perfectly sanitary, clean and healthful and which will overcome all of the objections incident to the use in common by different people of drinking cups and glasses.

To this end my improved drinking cup comprises the various features and details of construction hereinafter described and claimed.

In the accompanying drawing, in which my invention is fully illustrated, Figure 1 is a vertical sectional view of the parts of my improved drinking cup preliminary to inserting the inner paper section into the holder. Fig. 2 is an enlarged sectional view of the holder and of the inner paper section inserted therethrough, taken on the line 2—2 of Fig. 3. Fig. 3 is a bottom plan view of the parts as shown in Fig. 2. Fig. 4 is a view similar to Fig. 3, the clamping plates being closed; and Fig. 5 is a vertical sectional view of the finished cup ready for use.

Referring now to the drawing, my improved drinking cup comprises an inner section 1, which forms the receptacle proper 55 for the water or other liquid, and an outer section, designated as a whole by the reference letter A, which forms a holder for the inner section 1 and is adapted to receive said section and to support the same to prevent 60 collapsing in handling—as when drinking—when said inner section or receptacle 1 is filled with water. The inner section or receptacle proper 1 of my improved drinking cup forms a tube both ends of which are 65 initially open, and is made of paper, preferably indurated or waterproof paper of about the weight of ordinary wrapping paper. The holder A comprises a hollow or tubular body portion 2, which is preferably 70 made of suitable sheet metal. The opening in the body portion 2 of said holder is made of proper size and shape to receive the tubular paper section 1 of my improved drinking cup and to facilitate inserting the tubular 75 paper section 1 lengthwise therethrough, in the manner presently described, the upper edge of said body portion 2 is preferably flared as shown at 3. The holder A also comprises clamping means, said clamping means 80 being constructed and arranged to open and close and being adapted, when open, to permit a tube to be inserted into said holder in position for engagement by said clamping means and to be removed from said holder 85 and to seal the same when closed.

In the preferable construction shown, said clamping means comprises plates 4 and 5 pivoted to the lower end of the body portion 2 of said holder at opposite ends and at substantially diametrically opposite points, suitable bearing lugs 6 being formed on the body portion 2 of the holder to provide bearings for said clamping plates 4 and 5. The meeting edges of the clamping plates 4 and 95 5 are constructed and arranged to overlap or interlock when said plates are fully closed, thus providing for forming a fold in the portion of the paper section 1 engaged by the meeting edges of said clamping plates 4 and 5, which shall be relatively long and offset between its ends. As shown, the meeting edges of said clamping plates 4 and 5 are oppositely rabbeted, as shown at 100

7 and 8. Preferably, also, the clamping plates 4 and 5 are made of proper size to form a bottom for the body portion 2 of the holder A, on which said cup may rest 5 without danger of tipping over.

To insure that the clamping plates 4 and 5 shall grip the gathered portion of the paper section 1 of the cup firmly, said clamping plates 4 and 5 are made quite 10 heavy and the free end of the clamping plate 5 on which the underlying rabbet 8 is formed, is supported by means of a suitable stop on the body portion 2 of the holder A. As shown, said supporting stop consists 15 of the lower end of the handle 9 of the holder A, which is bent inwardly to form a hook or shoulder, as shown at 10. In order that the hook 10 may not project below the under side of the clamping plate 20 5, the extreme end of the clamping plate 5 is cut away on its under side, as shown at 11, to form an offset substantially equal to the thickness of the hook 10. To prevent the clamping plates 4 and 5 from cutting 25 or tearing the paper, the corners of the meeting edges thereof are preferably rounded or blunted. The holder A preferably comprises, also, suitable means located directly above the clamping plates 4 and 5 30 for gathering or folding the lower end of the paper section 1 of my improved cup as said paper section 1 is forced downwardly through the body portion 2 of said holder A. As shown, said gathering or folding 35 means comprises plates 12 and 13 secured to the inner sides of the tubular section 2 of said holder A, the upper ends of which are substantially flush with the inner surface of said tubular section 2 and which 40 converge downwardly. Said folding or gathering means also comprises noses 14 and 15 likewise secured to the inner surface of the body portion 2 of the holder A at substantially diametrically opposite 45 points between the plates 12 and 13, and which converge downwardly in substantially the same manner as said plates 12 and 13. Where, as shown in the drawing, the pivotal points of the clamping plates 4 and 50 5 are located inside of the side walls of the body portion 2 of the holder A, and the bearing lugs 6 project inwardly from the inner surface thereof, the gathering or folding plates 12 and 13 will preferably be 55 positioned so as to cover said bearing lugs 6 either wholly or in part, so that the lower edge of the paper section 1 shall not catch thereon when being inserted through the body portion 2 of the holder. 60 The paper section 1 of my improved cup is made longer than the body portion 2 of the holder, the relation being preferably such that when the paper section 1 of the cup is inserted in designed position in the holder A, the upper end of said paper sec-

tion 1 will project above the body portion 2 of the holder A such a distance, say from one and one-half to two inches, that it will be possible to drink from the paper section 1 without having the lips come into contact with any part of the holder. 70

The manner of using my improved cup is as follows; the description beginning with the holder A empty: The first step consists in inserting the paper section 1 into the holder A. Preliminary to this step the clamping plates 4 and 5 are turned pivotally outward into the position shown in Fig. 3, leaving the lower end of the body portion 2 of the holder A below the folding means open and unobstructed. The paper section 1, distended into tubular shape, is then inserted from top to bottom through the body portion 2 of the holder, until it projects below the clamping plates 4 and 5. As the lower end of said paper section 1 passes the gathering or folding plates 12 and 13 and the noses 14 and 15, it will be partially gathered or folded inwardly in proper position for engagement by the clamping plates 4 and 5. The clamping plates 4 and 5 are then closed with a firm pressure which operates to clamp the sides of the paper tube 1 between the meeting edges thereof, so as to seal the same and 95 render it water tight. 90

My invention contemplates the use of any desired or approved means for opening and closing the clamping plates 4 and 5, but such means forms no part of the present invention and it has therefore been considered undesirable to illustrate or describe such means in detail. 100

My invention contemplates that each paper section 1 shall be used but once and shall then be discarded, each paper section 1 after being used, being removed from the holder and a new and unused paper section inserted therein. Such use necessarily requires that a supply of the paper sections 1 be provided so as to be readily available when wanted for use. In order to economize space, said paper sections 1 will preferably be furnished flat, it being necessary to distend the same before inserting them into the holder. Likewise, to facilitate inserting said paper sections 1 in tubular form through the tubular body portion 2, a suitable former or die 16, is provided, said former being slightly smaller than the bore of the tubular section 2 of the holder A. The paper sections 1, after being distended, are placed over the die or former 16, which is then inserted into the tubular section 2 of the holder A. When the lower end of said plunger strikes the folding plates, it is raised inside of the paper section 1 and is again depressed with said paper section, thus causing said paper section to project beyond the clamping plates in the manner 125 130

desired. After the cup has been otherwise finished, the die or former 16 will preferably be forced down into the same so as to make the lower end thereof conform substantially to the shape of said die or former 16. To permit air to escape past said die or former, it is provided with suitable vent holes or openings which extend lengthwise through the same, as indicated at 17.

10 I claim:—

1. A holder for a paper vessel comprising an inclosing frame for said vessel, and clamping means constructed and arranged to open and close and adapted when open to permit said paper vessel to be inserted into said holder in position for engagement by said clamping means, and when closed to seal the lower end of said paper vessel, substantially as described.

20 2. A holder for a paper vessel comprising an inclosing frame for said vessel, and clamping means constructed and arranged to open and close and adapted when open to permit said paper vessel to be inserted into said holder in position for engagement by said clamping means, and when closed to seal the lower end of said paper vessel, said holder also comprising folding means adapted for gathering or contracting the lower 25 end of said paper vessel, substantially as described.

30 3. A holder for a paper vessel comprising a body portion adapted to receive said paper vessel and clamping plates supported on said body portion and movable toward and from each other and adapted when separated to permit said paper vessel to be inserted into said holder between said clamping plates, and when closed to grip said paper vessel between the meeting edges of 35 said clamping plates and thereby to seal the lower end thereof, substantially as described.

40 4. A holder for a paper vessel comprising a body portion adapted to receive said paper vessel and clamping plates supported on said body portion and movable toward and from each other and adapted when separated to permit said paper vessel to be inserted into said holder between said clamping plates, and when closed to grip said paper vessel between the meeting edges of 45 said clamping plates and thereby to seal the lower end thereof, the meeting edges of said clamping plates being constructed and arranged to interlock with each other when closed, substantially as described.

50 5. A holder for a paper vessel comprising a body portion adapted to receive said paper vessel and pivotally supported clamping plates the adjacent edges of which are adapted to be separated and brought into contact with each other by pivotal movement of said plates, and when separated to 55 permit a paper vessel to be inserted into said

holder between the edges of said clamping plates and when closed to clamp said paper vessel between the meeting edges of said clamping plates and thereby seal the lower end thereof, substantially as described. 70

6. A holder for a paper vessel comprising a body portion adapted to receive said paper vessel and clamping plates supported on said body portion and movable toward and from each other and adapted when separated to permit said paper vessel to be inserted into said holder between said clamping plates, and when closed to grip said paper vessel between the meeting edges of said clamping plates and thereby to seal the 75 lower end thereof, the meeting edges of said clamping plates being rabbeted and a support for the free end of the underlying clamping plate, when closed, substantially as described. 80

7. A holder for a paper vessel comprising a body portion adapted to receive said paper vessel and clamping plates pivoted adjacent to their opposite ends to the lower end of the body portion of said holder so as to be 85 movable toward and from each other to effect separation and contact of the adjacent edges of said clamping plates and adapted when separated to permit said paper vessel to be inserted into said holder between said clamping plates and when closed to seal the lower end of said paper vessel, substantially as described. 90

8. A holder for a paper vessel comprising a body portion adapted to receive said paper vessel and clamping plates pivoted adjacent to their opposite ends to the lower end of the body portion of said holder so as to be 95 movable toward and from each other to effect separation and contact of the adjacent edges of said clamping plates and adapted when separated to permit said paper vessel to be inserted into said holder between said clamping plates and when closed to seal the lower end of said paper vessel, the meeting 100 edges of said clamping plates being rabbeted and a fixed support on the body portion of said holder for the free end of the underlying clamping plate when in closed position, substantially as described. 105

9. A holder for a paper vessel comprising a body portion, clamping plates pivoted thereto and gathering or folding means on the inner surface of the body portion of said holder, said folding means comprising oppositely positioned plates and noses located intermediate said plates, both said plates and said noses converging downwardly, substantially as described. 110

10. A holder for a paper vessel comprising a body portion, clamping plates pivoted to inwardly projecting lugs on the body portion of said holder, and gathering or folding means on the inner surface of the body portion of said holder, said folding means 115 120 125 130

comprising downwardly converging plates positioned above and which cover the lugs to which said clamping plates are pivoted, substantially as described.

5. 11. In a holder for paper vessels, an inclosing frame for said vessels, a clamping device at the lower end of said frame to receive and clamp the lower end of said vessel.

In testimony, that I claim the foregoing as my invention, I affix my signature in 10 presence of two subscribing witnesses, this 30th day of January, A. D. 1911.

FREDERIC P. MEYER.
